UNITED STATES PATENT OFFICE.

JOHN AUGUST BURKMAN, OF PORT ARTHUR, ONTARIO, CANADA.

HOT-WATER FURNACE.

Application filed December 21, 1925. Serial No. 78,922.

The present invention pertains to a novel hot water furnace designed to heat water for circulation or for the production of steam.

The principal object of the invention is the provision of a device of this character in which the hot gases issuing from the grate are caused to flow through super-heating flues surrounding the boiler before being emitted to the atmosphere. In the accomplishment of this object, the boiler consists of a double walled box-like member, the space within the double walls constituting the water space. The fire box is the interior of the boiler or the space surrounded by the inner members of the double walls. The bottom of the boiler is open for the purpose of receiving a grate. An outlet or passage is provided from the upper part of the fire box, through the rear wall of the boiler and into a flue which twice surrounds the remaining walls. The gases issuing from the fire box, in passing through this flue serve as a super-heating device for the contents of the boiler. Finally, the gases that have passed through the flue are exhausted to the atmosphere. A damper device is provided at the inlet of the flue, whereby the gases may be discharged from the interior of the boiler directly to the atmosphere.

30. The invention is fully disclosed in the following description and in the accompanying drawings in which—

Figure 1 is a perspective view of the boiler and attached flues;

35. Figure 2 is a similar view in a different position;

Figure 3 is a longitudinal vertical section;

Figure 4 is a vertical section on the line 4—4 of Figure 3;

40. Figure 5 is a section on the line 5—5 of Figure 3;

Figure 6 is a front elevation; and

Figure 7 is a detail section of one of the flue doors.

45. Reference to these views will now be made by use of like characters which are employed to designate corresponding parts throughout.

The body or boiler of the device is a box-like member 1 having double walls as shown in Figure 3 and an open bottom 2. This structure rests on a grate frame 3 which is supported upon a base casting 4. The forward wall 5 of the boiler has an opening 6 for charging, and the rear wall 7 has a passage 8 communicating with the flue de-

scribed in detail below. Tubes 9 are extended between the forward and rear walls, in communication therewith, as illustrated in Figure 3.

The grate frame has a rectangular opening 10 substantially the same size as the recess 2 in the bottom of the boiler. The opening 10 is surrounded by a flange 11 for better supporting the boiler. The lower portion 11' of this flange supports a pair of rotatable grate bars 12 by means of cranks 13 extending from the bars into the flange. At the forward end, the cranks are extended beyond the flange 11 and are provided with inter-engaging segments 14 as shown in Figure 4. One of the cranks is still further extended as at 15 through the front wall of the base 4 and is there equipped with a handle 16 by which it may be turned to effect a rocking movement of the grate bars. A stop pin 17 projecting from the rear part of the flange 11 limits the movement of the bars.

The boiler is surrounded by a circuitous flue which starts at the rear wall of the boiler, passes twice along the remaining walls, and ends near its inlet. The inlet part of the flue comprises an inclined branch 18 communicating with the passage 8 and co-extensive therewith. This branch extends downwardly to the bottom of the right hand side 19 of the boiler. From this point it continues along the following course: A conduit 20 extending to the front end of the side 19, a conduit 21 along the forward end 22 of the boiler, a conduit 23 from the lower forward corner to the upper rear corner of the wall 24 of the boiler, a horizontal conduit 25 from the upper rear corner to the upper forward corner of the wall 24, a conduit 26 along the upper edge of the front wall 22, a conduit 27 from the upper forward corner to the upper rear corner of the wall 19, and finally the outlet end 27' which lies adjacent the inlet 18 and is open as shown in Figure 1.

The upper end of the inlet branch 18 is open and may be closed by a damper 28 mounted therein and operable by a rod 29 projecting therefrom. This rod may be suitably connected by a chain or similar device for operation from the floor. In consequence of the described arrangement of flues, the hot gases rising from the grate pass along the tubes 9 and through the passage 8. If the damper 28 is closed the gases proceed

along the various flue branches in the sequence in which they are described above. These conduits may be welded or otherwise secured to the boiler which is preferably cast 5 as an integral structure.

The boiler and flues are enclosed by a forward wall 30, a rear wall 31, and lateral walls 32. These may be formed as integral parts of the flue conduits if desired. On the 10 upper edges of these walls is supported a hollow rectangular plate 33 at the rear end of which is formed a collar 34 for connection to a chimney. This collar is elongated as shown in Figure 5, being placed directly 15 over and co-extensive with the aligned upper ends of the conduits 18 and 27'. Thus, the gases issuing from the outlet conduit 27' after passing through the other flue conduits, are exhausted into the chimney. It 20 will also be apparent that if the damper 28 is open, the gases will pass directly into the chimney from the interior of the boiler without flowing through the flue conduits. The enclosing structure is completed by means of 25 a top plate 35 resting on the frame 33 as shown more clearly in Figures 3 and 5.

The charging opening 6 in the forward wall of the boiler is normally closed by a fire door 36 hingedly mounted on the front 30 wall 30. Also, the forward wall of the base 4 has an ash door 37 in which is formed a draft damper 38 for obvious purposes.

The lower corners of the front upper conduit 26 are formed with apertures 39 as 35 shown in Figure 2. These apertures are normally closed by means of doors 40 mounted on the front wall 30 as shown in Figures 6 and 7. When these doors are removed access to the flues for cleaning the same is possible. Each door 40 is supported in closed 40 position by means of a pair of latches 41 projecting from the vertical edges thereof and receivable upon lugs 42 formed with the front wall 30 as shown in Figure 7.

45 While a specific embodiment of the invention has been illustrated and described, it is

to be understood that various alterations in the details of construction may be made without departing from the spirit of the invention as indicated by the appended 50 claims.

Having thus fully described the invention, what I claim as new and desire to protect by Letters Patent is:

1. A hot water furnace comprising a double walled boiler having an open bottom, the water space being in the double walls thereof, a flue commencing at the rear wall of the boiler and twice surrounding the remaining walls, returning to the rear wall, said rear wall having a passage permitting communication between the interior of the boiler and the inlet end of the flue, the remaining end of the flue being open, another wall of the boiler having a through recess permitting access to the interior of the boiler, said recess being disposed above the grate, a fire door normally covering said recess, and tubes extending between opposite walls of the boiler and communicating therewith. 55

2. In a furnace including a rectangular shaped boiler having a combustion chamber and a double walled water circulating chamber and provided with an outlet for the combustible gases in the upper rear wall, a gas 75 circulating flue in communication with the said outlet extending diagonally downward from the upper central portion of the rear wall to the lower corner, extending forwardly along one side wall and laterally 80 across the lower edge of the front wall and extending upon the opposite side from the lower forward corner to an upper position at the rear end and then continuing about the upper edges of the side walls and 85 front wall to form a return flue and communicating at the rear wall with an exhaust flue.

In witness whereof I have hereunto set my hand.

JOHN AUGUST BURKMAN.
